UNITED STATES PATENT OFFICE

122,264

DESIGN FOR A BIRD FEEDING STATION

Horace H. Francine, Ambler, Pa.

Application March 12, 1940, Serial No. 90,843

Term of patent 14 years

To all whom it may concern:

Be it known that I, Horace H. Francine, a citizen of the United States of America, residing at Ambler, in the county of Montgomery and State of Pennsylvania, have invented a new, original, and ornamental Design for a Bird Feeding Station, of which the following is a specification, reference being had to the accompanying drawing, forming part thereof.

Of the drawing:

Fig. 1 is a front elevation of a bird feeding station showing my new design;

Fig. 2 is a side elevation; and

Fig. 3 is a plan view of the same.

I claim:

The ornamental design for a bird feeding station, as shown.

HORACE H. FRANCINE.
